RALPH O. CLARK, OF MEMPHIS, TENNESSEE

TABLE LEG HINGE AND LATCH

Application filed September 14, 1931. Serial No. 562,702.

This invention relates to improvements in hinges and latches for folding legs for tables.

The principal objects of this invention are:—

To provide a leg hinge which is positioned in the corner formed by the top rails which constitute the frame supporting the top of the table, which hinge braces the rail corner and the leg hinged thereto;

To provide means for latching the leg in open or using position relatively to the hinge and rails;

To provide means for supporting the latching pin whereby it will automatically drop into place when the leg is moved to open position and to provide means in such a latch for automatic wedging action of the latching parts.

The means by which the foregoing and other objects are accomplished and the manner of their accomplishment will readily be understood from the following specification on reference to the accompanying drawings, in which:

Fig. 1 is a side elevation of the upper end of a table leg in opened position together with a hinge and latch therefor;

Fig. 2 is a similar view with one leg of the hinge member cut away on the line II—II of Fig. 4, to show the leg plate of the latch;

Fig. 3 is a corresponding view of Fig. 2, showing the leg turned to folded position; and

Fig. 4 is a sectional plan taken on the line IV—IV of Fig. 1.

Referring now to the drawings in which the parts are referred to by numerals, 10 is a table leg, 11 a table top, and 12—13 rails constituting the top frame to which the top 11 is attached.

Secured in the corner formed by the rails 12—13 is a substantially U-shaped hinge member having a bottom 14 and legs 15—16 the bottom 14 being secured to the rail 12, preferably by screws 17, and the U leg 16 secured to the rail 13 as by screws 18.

Secured to one side of the table leg as by a screw 19 is a leg plate 20 which plate and the leg are apertured to receive a hinge pin

21. This pin preferably is a bolt which also passes through corresponding holes in the U legs 15—16 and is either threaded directly into the leg 16, or it may screw into a nut 22 disposed in a suitable recess 23 in the rail 13. 55 The leg plate 20 is provided with a slot 24 which has a portion 25 of that edge which lies adjacent to the U bottom 14, substantially parallel to that bottom. The upper end 26 of the plate 20 is cut away around the 60 pin 21 as a center and the edge 27 is similarly relieved in order that the plate may turn around the pin 21 without binding against the table top. The leg 10 is cut out, and cut away to conform to the slot 24, and these cut 65 away portions of the plate 20.

The U leg 15 is provided with a latch pin slot 30 which slot lies below the pivot pin 21, extending downward and toward the U bottom so that the bottom end of the slot 30 is 70 closer to the U bottom than is the upper end of the slot. Disposed in the slots 30 and 24 is a latch pin 31 one end 32, of which is loosely secured in the plate, 16, as by upsetting the end to prevent removal of the pin, 75 the hole in the U leg 16 being slightly larger than the pin 31, but smaller than this upset end.

The end of the pin 31 opposite the upset end 32 extends through the slot 24, and the 80 slot 30, and is preferably provided with a head 33 which may be grasped in moving the pin by hand to release it. In Figs. 1, 2 and 3 the pin is shown in section to indicate that this head has been cut off, this 85 being done to reduce complication of the view. In installing the device the nut 22, if used, is placed in the recess 23 and the U hinge member is secured in place as by the screw 17—18. Thereafter the leg 10 is 90 slipped into place, the slotted end passing to place over the pin 31, and the hinge pin 21 is inserted and engaged with the threaded plate 16, or the nut 22 as the case may be, and tightened until the leg 10 is so firmly held that it is necessary to use a moderate amount of force to move it from open to closed position or vice versa. 95

To set up a table which has been folded 100

it is only necessary to pull each leg in turn into open or using position.

It will be noted that when the leg is in folded position as shown in Fig. 3, the latch pin 31 is supported by the arcuate extension 25—A of the slot edge 25 so that there is no resistance of the pin to the opening movement of the leg and so that the pin automatically drops into place when the leg is in using position. Latching action of the pin begins as soon as the pin reaches the restricted lower portion of the slot 24. The actual latching is accomplished by the wedging of the pin 31 between the edge 25 of the leg plate slot and the opposite edge of the slot 30 in the hinge leg 15. Preferably the depth of the slots 30 and 24 is such that the pin 31 accomplishes its latching action well before it bottoms in the slots.

Having described my invention, what I claim is:

1. In a table leg hinge and latch, for a table having top rails, a U-shaped hinge member secured to the inner side of a rail, said member having a slot in one leg thereof, a table leg having its upper end disposed between the legs of said member, a hinge bolt passing through said member legs and said table leg, a plate rigidly secured to said table leg adjacent the slotted leg of said member, said plate having a slot adapted to receive a latch pin, a latch pin loosely pivoted through one leg of said member, and having its opposite end projecting through the slots in said plate and the adjacent leg of said member.

2. In a leg hinge and latch for a table having a top and rails, a U-shaped hinge member disposed against the inner sides of said rails at a corner formed by two of them, said member having one leg thereof secured to one of said rails, and its bottom to the other thereof, said member having a pin receiving slot in the unsecured leg thereof, a table leg having its upper end disposed between the legs of said member, a hinge bolt passing through said member legs and said table leg, a plate rigidly secured to said table leg adjacent the slotted leg of said member, said plate having a notch adapted to receive a latch pin, and a latch pin loosely hinged through the secured leg of said member, and having its opposite end projecting through the slots in said plate and the adjacent leg of said member.

3. In a table-leg hinge and latch, a U-shaped hinge member secured to the inner sides of a table-top rail, said member having a pin receiving slot in one leg thereof, the lower part of said slot being closer to the bottom of said member than the upper part thereof, a table leg having its upper end disposed between the legs of said member, a hinge bolt passing through both legs of said member, a plate secured to said table leg ad-

jaacent said slotted leg of said member, said plate having a slot adapted to receive a latch pin the latching edge of said slot adjacent the bottom of said U member being substantially parallel with said bottom and a latch pin, having one end loosely secured through one leg of said member and having its opposite end projecting through said plate slot and the slotted leg of said member adjacent thereto, said table leg being cut away to conform to the slot in said leg plate.

In testimony whereof I hereunto affix my signature.

RALPH O. CLARK.
